UNITED STATES PATENT OFFICE.

MORTIMER J. GOLDEN, OF BROOKLYN, NEW YORK.

WATERPROOF CROWN FOR WATCHES.

1,295,023.

Specification of Letters Patent.

Patented Feb. 18, 1919.

Application filed November 17, 1917. Serial No. 202,552.

To all whom it may concern:

Be it known that I, MORTIMER J. GOLDEN, a citizen of the United States, and a resident of the city of New York, borough of Brooklyn, in the county of Kings and State of New York, have invented a new and Improved Waterproof Crown for Watches, of which the following is a full, clear, and exact description.

10 This invention relates to waterproof watches and has to deal more particularly with improved means for preventing the entrance of moisture into the watch case at the winding and setting stem.

15 The invention has for its general objects to improve the construction and operation of devices of this character so as to be reliable and efficient in use, comparatively simple and inexpensive to manufacture, and so designed that the winding and setting of the watch can be easily and quickly effected and waterproofness positively insured.

20 A more specific object of the invention is the provision of a simple and novel crown and clamping and unclamping means therefor to normally hold the crown seated in water-tight condition, and to permit the crown to be released when the watch is to be wound or set.

25 30 With such objects in view, and others which will appear as the description proceeds, the invention comprises various novel features of construction and arrangement of parts which will be set forth with particularity in the following description and claims appended hereto.

35 The present invention is designed as a modified form of the invention forming the subject matter of an application filed by me October 6, 1917, Serial No. 195,007.

40 45 In the accompanying drawing, which illustrates one embodiment of the invention and wherein similar characters of reference indicate corresponding parts in all the views. Figure 1 is a fragmentary view of a watch, showing the improved crown and the clamping means therefor;

50 Fig. 2 is an enlarged sectional view on the line 2—2, Fig. 1;

55 Fig. 3 is a similar view showing the clamping cap or ring in unclamping position to permit the crown to be operated for winding or setting the watch;

Fig. 4 is a sectional view on the line 4—4, Fig. 2;

Fig. 5 is a perspective view of the hub or seating section of the crown.

Referring to the drawing, 1 designates a watch case which has a pendant 2 suitably fastened thereto and passing through the pendant is a tube 3 that accommodates the winding and setting stem 4, and in the tube is a clutch 5 that coöperates with the oppositely coned portion 6 of the stem to hold the stem in winding and setting relation, as shown by the full and dotted lines, Fig. 3. Attached to the stem is the crown 7 for manipulating the stem.

The crown 7 is made up of a head 8 having a threaded opening 9 and a countersink 10, and into this opening screws the reduced threaded portion 11 of the hub or seating section 12 of the crown. This section 12 has an opening 13 provided with a right-hand screw into which screws the threaded extremity 14 of the stem 4. The pendant 2 is provided with a cylindrical recess 15 for accommodating the seating portion 12 of the crown, which latter has an external annular shoulder 16, and the bottom of the recess 15 constitutes a seat 17, and between this seat and the bottom surface 18 of the seating section of the crown is a washer 19 of suitable material to constitute a packing, there being annular grooves 21 in the seating surfaces 17 and 18 into which the packing is pressed to produce better joints to exclude moisture. The packing may be saturated with oil to improve its waterproofness.

The crown is normally clamped, as shown in Fig. 2, by means of a clamping ring or cap 22 which has a left-hand thread to engage the threaded circumference 23 of the pendant. The ring has internal flanges 24 and 25, the former of which normally engages the external shoulder 16 of the crown to draw the latter into the pendant and compress the packing. The other flange 25 is adapted to engage an external shoulder 26 on the pendant when the clamping ring is unscrewed, as shown in Fig. 3. In assembling the parts the flange 25 is cylindrical so that the clamping ring can be screwed onto the pendant, and then by a suitable tool the flange is turned in to the position shown, whereby the clamping ring is permanently 105

fastened to the pendant and cannot be removed.

In winding the watch it is first necessary to turn the clamping ring so as to unscrew it from the position shown in Fig. 2, to that shown in Fig. 3. This frees the flange 24 from the shoulder 16, so that the crown can now be turned to wind the watch spring. This unscrewing of the clamping ring also provides clearance between the flange 24 and shoulder 16 to permit the crown to be pulled outwardly to the dotted-line position, Fig. 3, to thereby enable the watch hands to be set by turning the crown.

15 After the head 8 of the crown is screwed to the central section 12, the attachment is made permanent by beading over the edge 27 of the threaded stud 11, so as to engage the countersink 10.

20 From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown 25 is merely illustrative and that such changes may be made when desired as fall within the scope of the appended claims.

It is to be understood that the present application relates specifically to a construction involving a cap 22 formed with the flanges 24, 25 engageable respectively with the shoulder on the hub of the crown and the shoulder on the pendant; I do not claim in the present application the generic features 30 whereby a water-tight joint is formed at the exterior of the pendant, distant from the outer end thereof, by means of the relatively turnable cap or like instrumentality, the generic features common to the two applications being claimed in my prior application 35 above named.

Having thus described my invention, I claim as new and desire to secure by Letters Patent:

1. The combination of a watch case, a pendant connected therewith and having an external thread and having a reduced portion lying between the thread and the case, whereby an annular external shoulder is formed, there being a recess in the outer face of the pendant, a packing in the said recess, a crown having a hub of such diameter as to enter the recess to engage the packing, and said hub being circumferentially reduced to form an annular shoulder, and a clamping ring threaded on the pendant and having internal flanges spaced apart a distance greater than that between the shoulders of the pendant and hub, whereby one flange engages the pendant shoulder to limit the unscrewing of the clamping ring in a direction to free the crown for axial and rotative movement and the other flange being adapted to engage the shoulder of the hub when the clamping ring is screwed tight for producing a water-tight joint between the crown and pendant.

2. The combination of a watch case a pendant thereon having an external thread and reduced in diameter at a point between the thread and the case, whereby an annular external shoulder is formed, a crown having a hub reduced at an intermediate portion to form an annular external shoulder, a packing between the hub and pendant, and a clamping ring threaded on the pendant and having internal annular flanges spaced apart a greater distance than that between the shoulders of the pendant and hub, whereby the turning of the ring in one direction 85 clamps the pendant and crown together in water-tight relation and turning in the opposite direction unclamps the crown while the ring maintains a threaded engagement with the pendant.

MORTIMER J. GOLDEN.
